UNITED STATES PATENT OFFICE.

EDMON W. KELLER, OF CRIPPLE CREEK, COLORADO.

AUTOMATIC TRAIN-STOP MECHANISM.

1,134,868.

Specification of Letters Patent.

Patented Apr. 6, 1915.

Application filed August 11, 1913. Serial No. 784,198.

To all whom it may concern:

Be it known that I, EDMON W. KELLER, a citizen of the United States, residing at Cripple Creek, in the county of Teller and State of Colorado, have invented certain new and useful Improvements in Automatic Train-Stop Mechanism; and I do hereby declare the following to be a full, clear, and exact description of the invention, such as will enable others skilled in the art to which it appertains to make and use the same.

This invention comprehends improvements in automatic train stop mechanisms, and relates more particularly to that type wherein means are provided for closing the throttle valve and applying the airbrakes when a train runs by a signal set at danger.

One of the objects of the invention is to provide a device of this nature which shall be of extremely simple construction, cheap to manufacture and install and very efficient.

Another and more specific object of the invention is to provide a spring actuated lever to which may be connected a number of devices, such as the throttle lever, airbrake valve, whistle, etc., a latch for normally holding said lever against the action of a spring and diametrical operating means for tripping said latch to allow the lever to be swung.

With these and other objects in view, as will become more apparent as the description proceeds, the invention consists of certain novel features of construction, combination and arrangement of parts, and will be hereinafter fully described and claimed.

For a complete understanding of my invention, reference is to be had to the following description and accompanying drawings, 40 in which—

Figure 1 is a diametrical view showing that portion of my device which is adapted to be carried by a locomotive, Fig. 2 is an edge elevation of the signal operated obstacle, Fig. 3 is a side elevation of the obstacle, and Fig. 4 is a detail view of the latch carried by the throttle lever.

Referring in detail to the drawing by numerals, 5 designates a portion of a locomotive boiler, 6 a pivoted throttle lever, 7 the engineer's valve, and 8 the running board of a locomotive. The throttle lever carries a sliding latch 9 which is adapted to engage a toothed segment 10 and lock said lever in any desired position. This latch may be manually operated in the usual manner by

means of a latch rod 11 and grip, or handle 12.

In the preferred embodiment of my invention I provide a base plate 13 of any size and shape, said plate being fixed to the boiler 5 at any suitable place. A lever 14 is pivoted intermediate its ends to the plate 13 and has a long upper arm and a short lower arm. A contractile spiral spring 15 is securely connected to the extremity of the upper arm of the lever and to the base plate 13. The spring tends to draw the upper end of the lever 14 away from the throttle lever 6. A flexible connection 16 is secured at one end to the top of the lever 14 and at its other end to the latch 9, said connection extending through an eye 17 carried by the throttle lever directly under the latch. A second flexible connection 18 is also secured at one end to the lever 14 adjacent the upper end thereof and at its other end to the handle 19 of the engineer's valve 7. This connection 18 passes over suitably positioned guide pulleys 20 and 21.

To hold the lever 14 in the position shown in Fig. 1 against the tension of the spring 15, I provide a spring latch 22. This latch is rigidly secured at one end to the base plate 13, extends under the lower end of the lever 14, and has a head 23 which engages one end of said lever to hold the latter in a vertical position. A flexible connection 24 is connected at one end to the latch 22 adjacent the head 23 thereof and at its other end to a trip lever 25 which is pivoted intermediate its ends to a bracket 26 suitably positioned upon the running board 8. A guide pulley 27 is provided so as to cause the connection 24 to exert a downward pull upon the latch 22.

For engagement with the trip lever 25, in case of danger, I provide an obstacle 28 in the form of an elongated bar. This bar is rigidly secured to the horizontal shaft 29 which extends at right angles to the track rails 30 and which is journaled through bearings 31. A cross bar 32 is rigidly secured to the outer end of the shaft 29 and has connected to its extremities the wires 33, said wires running to a semaphore arm, not shown.

When the semaphore is positioned to indicate danger, the wires 33 cause the rod 29 to be rotated and raise the obstacle 28 into a vertical position. Should the engineer endeavor to run by this obstacle, the latter

will engage the trip lever 25 and rotate the same about its pivot so as to cause the latch 22 to be swung downwardly away from engagement with the lever 14. As soon as this happens, the spring 15 will swing the upper end of the lever 14 away from the throttle lever 16 and engineer's valve 17, causing the flexible connections 16 and 18 to actuate the throttle lever and handle 19 respectively. A pull upon the connection 16 releases the latch 9 from the segment 10 and swings the throttle lever so as to shut off the flow of steam to the cylinders of the locomotive. A pull upon the connection 18 swings the handle 19 so as to release air from the train line and apply the airbrakes. It will be understood that the lever 14 may also be made to operate other devices, such as a whistle and sand-box, if desired. One of the advantages of my device arises from the fact that but a slight downward pull is necessary to disengage the latch 22 from the lever 14, this latch being of a spring material can be readily sprung from engagement with the lever no matter how strong the spring 15 may be.

From the foregoing description taken in connection with the accompanying drawings, it will be apparent that I have provided an extremely simple, efficient and reliable automatic stop mechanism for locomotives, which will greatly reduce the number of accidents, by making it impossible for a train to run by a danger signal.

While I have shown and described the preferred embodiment of my invention, it

will be understood that minor changes in construction, combination and arrangement of parts may be made without departing from the scope and spirit of the invention 40

as claimed.

Having thus described my invention, I claim:—

In a train stopping mechanism of the character described, the combination with a locomotive having a boiler and a swinging throttle lever and an engineer's valve, a plate secured to the boiler adjacent the throttle, a second lever pivotally secured to said plate intermediate its ends, its upper 50 end being reduced and having a flexible connection secured thereon, the free end of said flexible connection secured to the latch of the throttle lever, a latch secured to said plate adjacent the lever thereon, its free 55 end to engage the lower end of said second lever and hold same in a vertical position, a coil spring attached to the upper end of said second lever and its opposite end secured to the plate, a flexible connection secured to the free end of said latch and extending downwardly and outwardly to a pivoted rod, said rod adapted to engage the object on the track whereby said latch will be released and the throttle operated. 60 65

In testimony whereof I affix my signature in presence of two witnesses.

EDMON W. KELLER.
